UNITED STATES PATENT OFFICE.

EDWIN WALDEN, OF LYNN, MASSACHUSETTS.

DESIGN FOR A RESERVOIR FOR PENS.

SPECIFICATION forming part of Design No. 31,852, dated November 21, 1899.

Application filed October 23, 1899. Serial No. 734,590. Term of patent 3½ years.

To all whom it may concern:

Be it known that I, EDWIN WALDEN, a citizen of the United States, residing at Lynn, in the county of Essex, State of Massachusetts, have invented a certain new and original Design for a Reservoir for Pens, of which the following is a specification, reference being had therein to the accompanying drawings.

In the drawings, Figure 1 is a plan of a reservoir for pens, showing my design. Fig. 2 is a bottom view thereof. Fig. 3 is an edge view thereof. Fig. 4 is a longitudinal section on line 4-4 of Fig. 1. Fig. 5 is a cross-section on line 5-5 of Fig. 1. Fig. 6 is a cross-section on line 6-6 of Fig. 1.

As shown in the drawings, the leading or material features of my design are the curved shape of the shank 1, the same being convex on its upper face and concave on its under face; also, the reversely-curved shape of the

waist or body portion 2, the latter being concave on its upper face and convex on its under face; also, the inclined or oblique nose or nib 3, the somewhat-pronounced angle at 4, where such nose or nib joins the waist or body portion, and the hips 5 at opposite sides of the juncture of the nose or nib and waist or body portion.

Having described my invention, what I claim as new, and desire to secure by Letters Patent, is—

The design for a reservoir for pens, as herein shown and described.

In testimony whereof I affix my signature in presence of two witnesses.

EDWIN WALDEN.
